UNITED STATES PATENT OFFICE.

MARTIN ZIMMERMAN, OF JEROMEVILLE, OHIO.

GRAIN-METER.

No. 892,492.

Specification of Letters Patent.

Patented July 7, 1908.

Application filed October 17, 1907. Serial No. 397,821.

To all whom it may concern:

Be it known that I, MARTIN ZIMMERMAN, a citizen of the United States, residing at Jeromeville, in the county of Ashland and 5 State of Ohio, have invented certain new and useful Improvements in Grain-Meters, of which the following is a specification.

My invention relates to improvements in grain-meters, and, more particularly, to that 10 class or type which are adapted to automatically measure out certain charges or units of measure by the weight thereof as distinguished from quantity or volume.

The primary object of the invention is to 15 provide a generally-improved device of this class which will accurately and rapidly weigh the grain as it is delivered from the separator, elevator, or other source of supply and discharge it into a sack, bin, wagon-box or other 20 receiving or storing receptacle, and which will be much better adapted to its intended purposes than any other device of this class with which I am acquainted.

With these and other ends in view, the 25 invention consists in the novel construction, arrangement and combination of parts, hereinafter described, illustrated in the accompanying drawings, and particularly pointed out in the appended claims.

30 Referring to the drawings, forming a part of this specification, Figure 1, is an elevation of the face or registering side of the improved grain-meter in its normal position. Fig. 2, a view of the front side of the same showing 35 manner of attaching to the side of a thresher or grain-separating machine. Fig. 3, a front view of the recording dial-disk mechanism and casing attached to the fulcrum end of the poised yoke-lever, the front plate of casing 40 being removed in this figure and in Fig. 1, for the purpose of clearer illustration of the parts. Fig. 4, a horizontal sectional view of the same, with attached lever, showing lever-fulcrum trunnion and lower end of movable 45 bar, carried by grain-drum, for operating cut-off-valves in feeding-hopper. Fig. 5, a detail view of the lower portion of the main 50 hopper provided with valved delivery-chutes or sacking spouts. Fig. 6, a view of the face 55 side of the grain-meter, the revolute grain-drum or receptacle being in its tilted position, a portion of the front wall of the depending feeding or throat portion of the feeding-hopper being broken away for the purpose of illustrating the oscillating cut-off-valves mounted thereon. Fig. 7, a trans-

verse sectional view of the intermittently-revolving grain-drum or receptacle and the lower and upper portions of the feeding and delivery hoppers, respectively, the parts 60 being shown in the position they occupy just prior to the depression or tilting of the grain-drum and the initial revolving movement of the same. Fig. 8, a similar view of the same, the grain-drum being at its initial filling position, the last portion of the preceding charge or measure passing out. Fig. 9, a similar view of the same, the grain-drum or receptacle being in its tilted and initial revolving and discharging position, the cut-off-valves 70 in the lower portion of the feeding-hopper being closed to cut off the ingress of the grain while the grain-drum is being revolved. Fig. 10, a detail view of the cut-off-valves and the operating mechanism attached thereto. Fig. 75 11, a plan view, on a reduced scale, of the poised yoke-lever or scale-beam and adjustably-mounted counter-weight carried thereby.

Similar numerals of reference designate 80 like parts throughout all the figures of the drawings.

The improved grain-meter comprises a feeding-hopper or trough, a grain-charge receiving and delivery hopper, and an intermediate intermittently-revolving poised grain-drum or receptacle.

The upper feeding-hopper or trough 1, is provided with a depending feeding or throat portion 2, forming an inlet-opening adapted 90 to direct or feed the grain into the grain-drum or receptacle, as hereinafter described, and, in the present instance, said hopper or trough is open at one end to receive the end of the grain delivery-trough 3, (see Fig. 2) of 95 the grain-separating-machine to the side of which the meter is attached, as shown in Fig. 2, and hereinafter described.

The main body portion 4, of the grain-charge receiving and delivery hopper is substantially 100 semi-cylindrical in form to receive and take over one half of the grain-drum when the latter is in its depressed and revolving discharging-position, and is provided with a depending portion 5, forming an outlet or discharge-opening 6, for the charge of grain received from the grain-drum or receptacle above.

A grain-charge delivery chute 7, is removably-mounted beneath the depending-portion 5, of the grain-charge delivery-hopper and is 110 secured at its upper edges about the lower edges of said depending-portion 5, by means

of a series of bolts and nuts 8. The lower outer side of the delivery-chute 7, is provided with branching delivery-chutes or sacking-spouts 9, provided with a common swinging cut-off or diverting valve-plate 10, and operating-handle 11, whereby the grain may be alternately diverted from one sacking-spout to the other. The outer ends of the spouts 9, are preferably provided with iron brace-frames 12, and are braced with respect to the hopper body portion 4, by means of a pair of outwardly and downwardly-extending iron straps or brace-members 13, the lower ends being turned over and about forming heads 14, over which may be secured the upper edges of the sacks by means of the movable cam-lever sack-securing members 15. The upper ends of the brace-members 13, are secured to the projecting ends 16, of the heads of the hopper 4, by means of bolts and nuts 17, said bolts and nuts also securing the lower ends of a second pair of iron brace-straps or members 18. The upper ends of the brace-straps or members 18, are secured to the under side of the ends of the cross-bars or members 19, supporting the rear ends of the feeding-hopper or trough 1, and extending over and secured to the upper side of a horizontal-beam 20 (see Fig. 2) of the grain-separating-machine. The upper attached ends of the brace-members 18, together with attaching straps or clips 21, below, securing the upper rear sides of the hopper body 4, to the upper edge of a horizontal-board 22 (see Fig. 2) form the attaching and supporting means for securing the meter to the side of the separator body. The feeding-hopper or trough 1, is secured to and supported above the hopper-body 4, at its rear, by means of a pair of vertical iron-straps 23, and, at its front, by means of brace-bars or rods 24. The face of the hopper body 4, is provided with an integral substantially semi-circular guide-member 25, carrying an inwardly-projecting friction guide-roller 26. The heads of the hopper body 4, are also provided with lever fulcrum-trunnions 27, (see Fig. 4) taking into and supporting the respective members of a poised yoke-lever or scale-beam 28, carrying an adjustably-mounted weight 29, adapted to counter-balance the weight of the grain-drum with its attachments, and the desired weight of the grain-charge to be contained within said grain-drum.

The intermittently-revolving poised grain-drum or receptacle comprises flanged heads 30, provided with an intermediate cylindrical body portion 31, said cylindrical body portion being provided with diametrically-opposite openings 32, one of which is adapted to receive and take over the depending feeding or throat portion 2, of the feeding-hopper or trough 1, and the other to discharge the weighed charge when the grain-drum is in its

primary normal and discharging positions, respectively, as shown most clearly in Figs. 1, and 7, and Figs. 6, and 9, of the drawings.

The grain-drum is provided with a central driving-shaft 33, the projecting ends of which are carried by and mounted within the ends of the members of the yoke-lever 28, one end of said driving-shaft 33, being provided with a driving-pulley 34, (see Fig. 2) carrying a belting 35, passing over a suitable pulley (not shown) of the grain-separating-machine, said belting being adapted to be stretched and revolve said grain-drum when the latter is depressed by the weight of the contained charge of grain, and maintained in operative relationship with said driving-pulley during one-half of one complete revolution of said grain-drum by the means hereinafter described.

As a means for effectually holding the grain-drum in its normal position and insuring its being stopped in proper position in its revolution, as well as effectually maintaining the belting 35, in operative relationship with the driving-pulley 34, during one-half of the revolution of the grain-drum, as above referred to, and preventing the latter from being raised or elevated during said one-half revolution, a disk-plate 36, is concentrically-mounted upon the face-head 30, of the grain-drum, forming a peripheral friction-track or way 36^a, for the friction-roller 26, and provided with diametrically - opposite recess-notches 37, designed to receive, take over and form a seat or pocket for the friction-roller 26, when the grain-drum has been revolved to its normal position.

When the weight of the grain within the grain-drum over-balances the counter-weight 29, the drum is moved downwardly stretching the belting 35, on the driving-pulley 34, the recess-notch 37, leaving the friction-roller 26, as shown in Fig. 6, of the drawings, and, as a further means of stretching the belting 35, at the initial movement of the grain-drum, an incline "a", is formed at one side of the notches 37, so that at the initial revolving of the grain-drum, the roller 26, will strike the said incline "a", and as the grain-drum moves the same will be moved downwardly still further as the incline "a", moves under the roller 26, and the latter mounts on and revolves up the said incline. It is obvious that as the track or way 36^a, moves under the roller 26, in the revolution of the grain-drum, the latter cannot be elevated by the counter-weight 29, until the other recess-notch 37, is reached, and that during said half revolution the belting 35, is effectually maintained in operative relationship with the driving-pulley 34.

As a means of cutting off any flow of grain through the feeding or inlet-opening of the feeding-trough 1, when the grain-drum is depressed by the weight of the contained grain,

and while the drum is being revolved, a vertically-movable bar 38, is provided and carried by the grain-drum, said bar 38, being provided at its lower end with a bearing-head 39, provided with a bearing-opening (see Fig. 4) taking over a bearing-hub 40, of the disk-plate 36, of the grain-drum, and terminating at its upper end in forked-arms 41, provided with bearing slots 42. The feeding or inlet-opening of the depending throat-portion 2, of the feeding-trough 1, is provided with rock-shafts 43, carrying cut-off-valves 44, said rock-shafts being provided with crank-arms 45, taking into the bearing-slots 42, of the forked-arms 41, so that when the bar 38, is moved downwardly with the downward movement of the grain-drum, the rock-shafts 43, will swing the attached valves 44, from the position shown in Figs. 7, 8, and 10, to the position shown in Figs. 6, and 9, thus cutting off the flow of grain when the grain-drum is in its depressed position, and vice versa.

As a means of separating the incoming and outgoing charges of grain within the grain-drum or receptacle a pair of grain-charge-separating-valve-plates 46, are pivotally-secured to the central driving-shaft 33 by means of hinge-straps 47, and said valve-plates 46, are adapted to have a limited movement within the grain-drum by means of radially-extending stop-bars 48, arranged in pairs on each side and separating the plates 46, and in inverted V-shape, said stop-bars 48, being secured to the inner sides of the heads 30, with the diverging ends thereof at the corners of the diametrically-opposite openings 32, of the grain-drum so that by virtue of the ends of said valve-plates encompassing said stop-bars said valve-plates will not be permitted to swing past the edges of the openings 32, but will straddle the same in inverted V-shape form beneath a charge of grain as shown in Figs. 7, and 9, and will separate the outgoing and incoming charges, following up the outgoing charge as shown most clearly in Fig. 8, of the drawings.

The registering of the several charges is effected by means of registering dial-disk mechanism mounted in a casing 49, secured to the front member of the poised yoke-lever 28, a central disk 50, (see Figs. 3, and 4) being provided with a hub-trunnion "b", keyed to the end of the driving-shaft 33, carrying the grain-drum and adapted to revolve therewith. The central disk 50, is provided with a peripheral actuating-stud or tooth 51, adapted to engage a tooth of a toothed registering-disk 52, and move the same one registering-space with each revolution, said disk (units) 52, actuating a second registering-disk (hundreds) 53, on the hub-trunnion "b", and said disk 53, actuating a third registering-disk (thousands) 54, all of said disks operating together in a well known

manner, said registering mechanism not forming the subject matter of the claims hereof. The casing 49, is preferably provided with a removable casing- or gear-cover 55, provided with sight-openings 56, as shown in Fig. 6, of the drawings.

It will be observed that the grain-drum is adapted to discharge at each half revolution, moving the unit recording-disk one space with each complete revolution, the present embodiment of the invention showing a grain-drum adapted to contain one-half bushel of grain, not including the sector-space formed above one of the peripheral openings of the drum by the grain-charge separating valve-plates.

From the foregoing description, taken in connection with the accompanying drawings, the operation and advantages of my invention will be readily understood.

Having thus described my invention, without having attempted to set forth all the forms in which it may be made, or all the modes of its use, I declare that what I claim and desire to secure by Letters Patent, is,—

1. In a grain-meter, a grain-drum provided with circumferentially-located openings and intermediate swinging valve-plates separating said openings.

2. In a grain-meter, a grain-drum provided with oppositely-disposed openings and pivotally-mounted valve-plates swinging between said oppositely-disposed openings.

3. In a grain-meter, a grain-drum provided with oppositely-disposed openings and intermediate swinging valve-plates, and stops for limiting the movements of said valve-plates whereby the same are caused to straddle said openings.

4. In a grain-meter, a grain-drum provided with openings in its cylindrical body portion, and a pair of grain-charge-separating valve-plates swinging between said openings.

5. A grain-meter, comprising a feeding-trough, a grain-charge delivery-hopper, an intermediate intermittently-revolving poised grain-drum provided with diametrically-opposite grain-receiving and discharging openings, means for poised said drum, valves mounted in said feeding-trough, means for closing said valves when said grain-drum is depressed, means for revolving said grain-drum, grain-charge-separating valves mounted within said grain-drum, and means for maintaining said grain-drum in depressed revolving-position when one of said openings of the grain-drum does not register beneath said feeding-trough.

6. A grain-meter, comprising a feeding-hopper provided with a feed-inlet-opening, a delivery-hopper provided with a grain-charge outlet-opening, an intermittently-revolving grain-drum poisedly-mounted and provided with diametrically-opposite grain-

receiving and discharging - openings normally-registering with said feed-inlet and grain-charge outlet-openings, means for poising said drum, cut-off valves mounted in said feeding-hopper and provided with means whereby the same are opened and closed when said poised grain-drum is moved to its normal and depressed positions, respectively, means for revolving said grain-drum, and a pair of pivotally-mounted grain-charge-separating valve-plates each adapted to swing within said grain-drum between said diametrically-opposite grain-receiving and discharging openings.

15 7. A grain-meter, comprising a feeding-hopper provided with a feed-inlet-opening, a delivery-hopper provided with a grain-charge outlet-opening, an intermittently-revolving grain-drum poised between said hoppers and provided with grain-receiving and discharging - openings normally - registering with said feed-inlet and grain-charge outlet-openings, means for poising said drum, cut-off valves mounted in said feeding-hopper and provided with means carried by said grain-drum whereby said valves are operated with the rise and fall of said grain-drum, grain-charge-separating valve-plates pivotally-mounted within said grain-drum and each swinging between said grain-receiving and discharging-openings, means for revolving said grain-drum, and means for holding said grain-drum in its depressed position during its revolution between said feed-inlet and grain-charge outlet-openings.

8. A grain-meter, comprising a feeding-hopper provided with a feed-opening, a delivery-hopper provided with an outlet-opening, a grain-drum poised between said hoppers and provided with openings normally-registering with said feed and outlet openings, means for poising said grain-drum, valves mounted in said feeding-hopper and provided with means whereby said halves are operated with the rise and fall of said grain-drum, valve-plates carried within said grain-drum and each swinging between said openings of the drum, means for holding said grain-drum in its depressed position during its revolution between said feed and outlet-openings, means for revolving said grain-drum, and means for stopping and holding the grain drum as against any movement on its axis when said openings are in registry with said feed and outlet openings of the hoppers, respectively, after the discharge of grain from the drum.

9. In a grain-meter, a grain-drum mounted on a driving-shaft and provided with circumferential openings and intermediate radially-extending swinging valve-plates mounted on said driving-shaft.

10. In a grain - meter, the combination with a feeding-hopper, a grain-charge delivery - hopper, an intermittently - revolving

poised grain-drum provided with circumferential openings adapted to simultaneously register with said feeding and delivery hoppers, means for poising said drum, and swinging valve-plates normally straddling one of said openings; of valves mounted in said feeding-hopper, means carried by said grain-drum for opening and closing said valves when the grain drum is moved to its normal and depressed positions, respectively, means for revolving said grain-drum when moved to its depressed position, and means for holding said grain-drum in its depressed position when said openings are not in registry with said feeding and delivery hoppers.

11. In a grain-drum, the combination with a feeding-hopper, a delivery-hopper, a poised grain-drum provided with openings adapted to register with said feeding and delivery hoppers, means for poising said drum, and swinging valve-plates normally closing one of said openings; of valves mounted in said feeding-hopper, means for operating said valves when said grain-drum is moved vertically, means for holding said grain-drum in its depressed position when said openings are not in registry with said feeding and delivery hoppers, and means for preventing said grain-drum from being turned on its axis when in its normal elevated position.

12. In a grain - meter, the combination with a poised grain-drum provided with a driving-pulley carrying a belting, means for poising said drum, means for revolving said drum, and a grain-charge delivery-hopper provided at its side with a friction guide-roller; of a circular friction - track or way formed on the end of said grain-drum and provided with oppositely - disposed recess-notches, said recess-notches being adapted to receive and form a seat for said friction guide-roller when said grain-drum is in its normal position and said friction-track taking under said guide-roller when said grain-drum is depressed.

13. In a grain-meter, a feeding-hopper, a grain-charge delivery-hopper, an intermittently-revolving grain-drum provided with circumferential openings adapted to register with said feeding and delivery hoppers, means for revolving said drum, means for poising said drum, swinging valve-plates normally straddling one of said openings, valves mounted in said feeding-hopper, and means carried by said grain-drum for opening and closing said valves when the grain-drum is moved to its normal and depressed positions, respectively.

14. In a grain-meter, the combination with a poised grain-drum, a feeding-hopper, means for poising said drum, means for revolving said drum, valves mounted in said feeding-hopper, and a delivery-hopper provided with a friction guide-roller; of a friction-track on said grain-drum and provided

with recess-notches, said friction-track passing under said guide-roller when said grain-drum is depressed and said recess-notches being adapted to form seats for said guide-roller whereby said grain-drum may be elevated to its normal position, and means carried by said grain-drum and connected to said valves whereby the latter are opened and closed by the elevation and depression of said grain-drum.

15. In a grain-meter, the combination with a feeding-hopper, a grain-charge delivery-hopper, a poised grain-drum provided with openings normally-registering with said hoppers, means for poising said drum, means for revolving said drum, and valve-plates swinging between and adapted to straddle said openings; of valves mounted in said feeding-hopper, means for maintaining 20 said grain-drum in depressed revolving position when said openings do not register with said hoppers, and means for opening and

closing said valves of the feeding-hopper when said grain-drum is moved to and from its normal position.

25

16. In a grain-meter, a grain-drum provided with circumferentially-located openings and radially located valve-plates swinging intermediate said openings.

17. In a grain-meter, a grain-drum provided with openings in its periphery and internal swinging valve-plates arranged to straddle said openings.

18. In a grain-meter, a grain-drum provided with peripheral openings and carrying 30 35 valve-plates pivotally mounted at its center and swinging between said openings.

In testimony whereof I have affixed my signature, in presence of two witnesses

MARTIN ZIMMERMAN.
